UNITED STATES PATENT OFFICE.

AUGUSTUS M. SAUNDERS, OF MCKEESPORT, PENNSYLVANIA, ASSIGNOR TO THE NATIONAL TUBE COMPANY, OF PITTSBURGH, PENNSYLVANIA, A CORPORATION OF NEW JERSEY.

METHOD OF AND APPARATUS FOR SHAPING PLATES OR PIPE-SKELP.

1,121,670.

Specification of Letters Patent. Patented Dec. 22, 1914.

Application filed October 20, 1910. Serial No. 588,177.

To all whom it may concern:

Be it known that I, AUGUSTUS M. SAUNDERS, of McKeesport, in the county of Allegheny and State of Pennsylvania, have invented certain new and useful Improvements in Methods of and Apparatus for Shaping Plates or Pipe-Skelp, of which the following is a full, clear, and exact description, reference being had to the accompanying drawings, forming part of this specification.

My invention relates to the shaping of rolled metal plates or pipe skelp by scarfing and bending preparatory to later heating and welding operations in the manufacture of lapweld pipes or tubes.

Heretofore, in making lapweld pipe the pipe skelp or plates have been scarfed in one operation, and the scarfed plates then drawn through a bending die in which they are bent into shape preparatory to heating and welding into pipes or tubes. The scarfing rolls usually have been located at a point remote from the drawing bench, on which the later bending operations were performed. In other cases, the draw bench and bending dies have been located at a distance from the scarfing rolls greater than the length of the longest plate or pipe skelp subjected to the bending and scarfing operations so that the longitudinal edges of the plates or skelp have always been scarfed before the bending operation is started and the scarfing and bending effected in two entirely separate and independent operations.

One object of this invention is to provide an improved method of shaping the plates or pipe skelp in a continuous operation, preparatory to heating and welding the scarfed and bent plates into tubes or pipes, in which the scarfing and bending operations are carried out simultaneously upon different portions of each pipe skelp or plate.

Another object of this invention is to provide improved apparatus for use in carrying out the steps of shaping the plates or pipe skelp comprising my improved method of continuous and simultaneous operation upon the plates and pipe skelp.

A further object of this invention is to provide a novel method of operating the scarfing rolls and bending dies and their operating mechanisms and to provide im-

proved means by which my novel method is carried out in accordance with this invention in effecting the shaping operations.

A still further object of this invention is to provide apparatus for shaping the plates or pipe skelp constructed and arranged in a manner which will be more fully described hereinafter.

In the accompanying drawings, Figure 1 is a longitudinal side elevation, partly in section, showing apparatus constructed and arranged in accordance with my invention, and adapted for use in carrying out the steps of the improved method forming part of this invention. Fig. 2 is a plan of the apparatus shown in Fig. 1. Fig. 3 is an end elevation showing the scarfing rolls forming part of this apparatus. Fig. 4 is a diagrammatic view showing the electrical connections to the motors forming the particular driving apparatus shown and described. Fig. 5 is a sectional end view of a pipe-skelp or plate before the scarfing operation. Fig. 6 is a similar sectional end view showing one manner in which the edges of the plates of Fig. 5 are scarfed in passing through the scarfing rolls forming part of the apparatus illustrated in connection with this invention. Fig. 7 is a sectional end view of a scarfed pipe-skelp or plate as bent in passing, after being scarfed, over the mandrel and through the bending dies on the draw bench forming part of the apparatus.

In these drawings, 2 designates a heating furnace in which the plates or pipe-skelp are placed and heated in preparation for the scarfing and bending operations.

The furnace 2 has an opening or doorway 3 in its end through which the heated plates are withdrawn in passing from the furnace into the bite of the scarfing rolls. Preferably, each end of the heating furnace 2 is provided with a doorway or opening, the plates being inserted through the opening in one end and withdrawn through the opening 3 in the opposite end. When found necessary or desirable, but one opening or doorway 3 may be used, the plates being both inserted and withdrawn through this opening in such case.

The opening 3 extends for substantially the entire width of the furnace 2 and in front of this end of the furnace are the

scarfing rolls 4 and 5 which are mounted in 5 housings 6. These housings are adjustably secured upon the shoes 7 forming part of the base plate 8, which is provided with rollers or wheels 9, rotatably mounted in bearings 10 on the lower side of the base plate 8 and a curved track 11 is provided beneath the base plate 8, upon which the rollers 9 are supported and turn when the 10 scarfing rolls are moved across the front of the furnace into different positions in front of the opening or doorway 3 of the furnace.

In front and on the discharge side of the scarfing rolls is a draw-bench 12 which also 15 is provided with rollers 13 which travel upon the track 14, the draw bench 12 being connected by the extension or arm 15 with the base plate 8 of the scarfing rolls so as to move with the scarfing rolls and base plate 20 upon which the scarfing rolls are mounted. The draw-bench 12 is provided with an endless chain 16 which passes around the idler sprocket wheel 17 and the driving sprocket wheel 18. The sprocket wheels are mounted 25 upon shafts 19 which are secured in bearings 20 on opposite ends of the draw bench. The shaft 19 of the driving sprocket wheel 18 is connected by means of the coupling boxes 21, 21, and spindle 22, with a spur gear 23 30 mounted on the shaft 24 which is secured in the bearings 25 forming part of a base plate 26 upon which the driving motor 27 also is mounted. The motor 27 is provided with a spur pinion which meshes with and 35 drives the spur gear on the shaft 24. A casing 24^a is shown surrounding these gears for the purpose of safety.

Idler wheels 28 are provided at suitable 40 intervals in the length of the draw bench on the under side of this bench to support and take up the slack in the draw chain 16 and prevent the lower strand of the chain dragging upon the floor beneath the draw bench.

The draw bench is pivoted at its outer 45 end, so as to permit the rear end to swing across the front of the heating furnace, the construction of the coupling boxes 21 and the spindle 22 permitting of the necessary swinging movement of the end of the draw bench in moving the scarfing rolls from one 50 side to the other of the door 3 in the heating furnace 2, in the operation of the apparatus. A platform 29 is suspended from one side 55 of the draw bench upon which the tongs-boy stands in manipulating the tongs in carrying out the plate bending operations.

The base plate 8 for the scarfing rolls is also provided with a driving motor 30 which is connected by the slow-down gears 31 and 60 32 to the scarfing rolls 4 and 5 to positively drive these rolls in scarfing the plates or pipe skelp.

The track 11 upon which the wheels 9 run in moving the base plate 8 is curved and this 65 track 11 is provided with a rack 33 having

teeth which mesh with the teeth in the pinion 34 which is mounted in bearings 35 on one end of the base plate 8. The shaft 36 upon which the spur gear 34 is mounted is provided with a spur gear 37 which meshes 70 with the spur pinion 39 on the counter-shaft 40, this shaft in turn being connected by the pinion 41 with the spur gear 42 on the armature of the motor 43 which is also mounted upon the base plate 8. This motor 43 75 is provided to move the draw bench 12 and the scarfing rolls in front of the heating furnace 2, to bring the scarfing rolls opposite plates located in different parts of the furnace 2. The platform 29^a is also supported upon and is movable with the draw bench and the base plate for the scarfing rolls.

Mounted on the entrance side of the scarfing rolls, between these rolls and the heating 85 furnace, are guides 44 by which the skelp or plates are directed into the scarfing rolls. On the discharge side of the scarfing rolls is a guide 45 and pivoted by the arm 46 to the 90 housings 6 of the scarfing rolls is an idler roller 47 which engages with the top surface of the heated skelp or plates, as they emerge from the scarfing rolls and prevents buckling of the heated skelp or plates.

In front of the scarfing rolls and the idler 95 roller 47 is a bending guide 48 having an upwardly extending arm 49 to which a lever 50 is pivoted. The lever 50 has a mandrel 51 secured on one end, the opposite end of this lever being provided with a counter-weight 52 for counter-balancing the mandrel 51.

Mounted on the track provided on the top surface of the draw bench 12 are the tongs 53 by which the end of the scarf'd plates are 105 grasped and drawn through the bending die 48. The tongs 53 are provided with wheels 54 and a lever 55 is secured at one end to the tongs, the opposite end of this lever 55 having a projection 56 which is adapted to 110 enter between the links of the draw chain 16 in operating the tongs by means of this chain. A handle 57 by which this lever is manipulated by the tongs-boy is also provided on the lever 55, as is best shown in 115 Fig. 1.

Between the scarfing rolls 4 and 5 and the bending dies 48 is a trigger formed of a bent lever 58 which is pivoted to a support 59 carried upon the extension or arm 15 by 120 which the draw bench 12 is connected to the base plate 8. One end of this lever is arranged to project upwardly through a suitable opening in the bottom of the guide 45 so as to be contacted by the advancing end and the under surface of the scarf'd plates or pipe skelp as they emerge from the scarfing rolls. The other end of the bent lever 58 or trigger is constructed so as to make 125 and break connection with one terminal 60 130

of an electric circuit leading to the motor 30 by which the scarfing rolls are driven from the generator 61 which supplies current to this motor and also to the motor 27 by means of which the chain 16 on the draw bench is actuated.

Secured upon the platform 29^a is a controller having push buttons 62 and 63 by means of which the motors 27 and 30 are stopped and started in the operation of the scarfing and bending apparatus.

In the operation of my improved apparatus, the plates are placed in the furnace 2 and are heated to the required temperature.

15 The plates are then successively removed from the furnace into the bite of the scarfing rolls, the guides 44 directing the forward end of the plates into the bite of the rolls. The rolls, which are positively driven through the gearing connecting the rolls with the motor 30, cause the plate to pass forwardly. When the forward end of the plate being scarfed engages with the upwardly projecting end of the pivoted lever

25 58, this end of the lever is depressed and its opposite end is lifted or raised, so as to break the electrical circuit to the motor 30, stopping this motor, and the scarfing rolls. The momentum of the revolving rolls, with

30 that of the scarfed plate traveling forwardly between the scarfing rolls, brings the forward end of the plates into close proximity with the receiving end of the bending guide 48 which is mounted on one end of the draw bench 12. The tongs-boy, who is upon the suspended platform 29, then moves the tongs 53 backwardly until the end of these tongs projects through the bending die 48 and engages with the forward

35 40 end of the partly scarfed plate, the forward movement of the plate then being stopped, or nearly so. The tongs-boy then moves the counter-weighted end of the pivoted lever 50 so as to bring the mandrel 51 into position within the bending guide 48 and simultaneously therewith places the projection 56

45 on the end of the lever 55 which is connected by one end to the tongs 53, into one of the spaces in the links of the draw chain 16.

50 The button 63 on the controller which is mounted upon the platform 29^a is then pressed, this operation completing the electric circuit through the motor 27 and the generator 61 so as to start this motor in operation and positively drive the endless chain 16.

55 The same movement of the button or switch 63 again starts the scarfing rolls driving motor 30 into operation and the remainder of the plate is scarfed and the plate as scarfed is drawn through the bending die so as to bend the flat scarfed plate into the approximately cylindrical shape shown in Fig. 7. When the plate or pipe-skelp is entirely drawn through the bending dies 48 the tongs-boy, who moves along

the platform 29, with the movement of the tongs and draw chain, lifts the lever 55 by the handle 57 so as to disengage the projection 56 on the lever from the chain 16 and after releasing the scarfed and bent plate or pipe-skelp, moves the tongs backwardly upon the track on the top of the draw bench 12 into position to again be brought into engagement with the forward end of another plate or pipe skelp to be bent. Before moving the tongs backwardly on the draw bench the bent plate is removed transversely of its length or sidewise, from the top of the draw bench in any desired manner. The above described operations are then continued upon successive pipe-skelp or plates so as to shape the plates by first scarfing a portion of the pipe skelp or plates and then bending the scarfed portions of the plates into the required shape for welding 85 into a pipe or tube, the bending operation upon part of the pipe skelp being performed simultaneously with the scarfing operation upon another portion thereof.

The advantages of my invention will be apparent to those skilled in the art. The apparatus is simple and is easily kept in repair. In using my improved apparatus in carrying out the steps of my novel method, the successive plates or pipe skelp are simultaneously scarfed and bent into the desired shape instead of first scarfing the plates in one operation and, after the completion of the scarfing operation, bending the plates in preparation for the later welding operations. When the plates being operated upon are partly scarfed, the scarfing mechanism is automatically brought to rest and remains inoperative until the tongs have been attached to the partly scarfed plate when the scarfing operation is completed simultaneously with the operation of bending the scarfed plates.

Modifications in the construction and arrangement of the parts may be made without departing from my invention as defined in the claims.

The type of motor for driving the different parts of the apparatus may be modified and the means for stopping and starting the driving motors may be changed and other modifications may be made.

I claim:

1. Apparatus for shaping pipe-skelp preparatory to welding into pipes or tubes, 120 comprising scarfing rolls, means for driving said rolls, a draw bench in front of said scarfing rolls having a bending die thereon, and means on the draw bench for drawing the skelp through the bending die, said bending die and scarfing rolls being arranged to operate simultaneously on lengthwise separate portions of the pipe skelp in scarfing and bending said skelp.

2. Apparatus for shaping pipe-skelp pre- 130

paratory to welding into pipes or tubes, comprising scarfing rolls, means for driving said rolls, a draw bench in front of said scarfing rolls having a bending die thereon, 5 and means actuated by the scarfed skelp for automatically stopping the scarfing rolls and interrupting the scarfing operation to permit attachment of partly scarfed skelp to the draw bench to thereby permit simultaneous engagement of the scarfing rolls and bending die on lengthwise separate portions of the skelp.

3. Apparatus for shaping pipe-skelp or 15 tubes comprising scarfing rolls, means for driving the scarfing rolls, a draw bench having a bending die in front of said scarfing rolls, means on the bench for drawing the scarfed plates or pipe-skelp through the bending die and means in the path of the 20 scarfed plate by which the scarfing rolls driving mechanism is stopped and the scarfing operation interrupted, while the partly scarfed plate is being attached to the drawing mechanism on the draw bench.

4. Apparatus for shaping pipe-skelp or 25 plates preparatory to welding into pipes or tubes comprising scarfing rolls, means for driving the scarfing rolls, a draw bench having a bending die in front of said scarfing rolls, means on the bench for drawing the scarfed plates or pipe skelp through the bending die and means in the path of the 30 scarfed plate by which the scarfing rolls driving mechanism is stopped and the scarfing operation interrupted, while the partly scarfed plate is being attached to the drawing mechanism on the draw bench, and

means for simultaneously starting the draw bench drawing mechanism and scarfing rolls 40 after securing the partly scarfed plate to the draw bench drawing mechanism.

5. Apparatus for shaping pipe-skelp or plates preparatory to welding into pipes or tubes comprising scarfing rolls, means for 45 driving the scarfing rolls, a draw bench having a bending die in front of said scarfing rolls, means on the bench for drawing the scarfed plates or pipe-skelp through the bending die and means in the path of the 50 scarfed plate by which the scarfing rolls driving mechanism is stopped and the scarfing operation interrupted, while the partly scarfed plate is being attached to the drawing mechanism on the draw bench, and 55 means for starting the draw bench drawing mechanism after securing the partly scarfed plate thereto and completing the scarfing and bending operations.

6. In the manufacture of pipes and tubes 60 the steps consisting in partly scarfing and heating skelp, interrupting the scarfing operation and attaching the partly scarfed skelp to a draw bench and then drawing the skelp through a bending die to thereby 65 operate simultaneously upon lengthwise separate portions of the skelp and bend the scarfed part of the skelp while completing the scarfing operation on the unscarfed portions thereof.

In testimony whereof, I have hereunto set my hand.

AUGUSTUS M. SAUNDERS.
